Fig. 4

Fig. 5

Fig. 6

Fig. 7

Fig. 8

Fig. 9

FIGURE 1 is an isometric view of a fireplace incorporating our new design.

FIGURE 2 is an isometric view of a modified form of a fireplace incorporating our new design.

FIGURE 3 is an isometric view of a second modified form of a fireplace incorporating our new design.

FIGURE 4 is a front elevation of the fireplace of FIGURE 1.

FIGURE 5 is a rear elevation of the fireplace of FIGURE 1.

FIGURE 6 is a fragmentary top plan of FIG. 1.

FIGURE 7 is a rear elevation of the fireplace of FIGURE 2.

FIGURE 8 is a rear elevation of the fireplace of FIGURE 3.

FIGURE 9 is a fragmentary top plan of FIG. 2.

For convenience of illustration, FIGURES 6 and 9 are fragmentary; i.e., partly broken away.

The flue and shield elements are broken away to indicate indeterminate length.

We claim:

The ornamental design for a fireplace, as shown and described.
